THOMAS R. KENNEDY, OF ROCHESTER, NEW YORK, ASSIGNOR TO CO-OPERATIVE FOUNDRY CO., OF ROCHESTER, NEW YORK, A CORPORATION OF NEW YORK.

GAS-BURNER.

1,285,733.

Specification of Letters Patent. Patented Nov. 26, 1918.

Application filed June 26, 1916. Serial No. 105,830.

To all whom it may concern:

Be it known that I, THOMAS R. KENNEDY, a citizen of the United States, residing at Rochester, in the county of Monroe and 5 State of New York, have invented certain new and useful Improvements in Gas-Burners; and I do hereby declare the following to be a full, clear, and exact description of the same, reference being had to the accompanying drawings, forming a part of this 10 specification, and to the reference characters marked thereon.

My invention relates to improvements in gas burners and particularly to burners 15 adaptable for use in connection with cooking stoves or ranges, and has for its object to provide a burner which may be used either for the burning of artificial or natural gas without removing or changing the position 20 of any of the parts of the stove other than the burner itself. My invention has for its further object to provide a burner capable of being positioned at relatively 25 different heights with respect to the top of a stove without changing the plane of elevation of the mixing chamber of the burner or the manifold connected therewith. A still further object of the invention is the provision of an invertible burner arranged 30 to discharge gas through the upper side thereof in its relatively different positions for the purpose of burning both artificial and natural gas. To these and other ends the invention consists in certain improvements 35 and combinations of parts, all as will be hereinafter more fully described, the novel features being pointed out in the claims at the end of the specification.

In the drawings:

40 Figure 1 is a plan view of a portion of a stove with the top removed showing the relative positions of the burners and manner of supporting the same;

Fig. 2 is a sectional view taken on line 45 2—2 of Fig. 1;

Fig. 3 is a longitudinal sectional view through one of the burners with the same in proper position for burning natural gas;

Fig. 4 is a similar sectional view with the 50 burner reversed for burning artificial gas;

Fig. 5 is an enlarged detail sectional view through the mixing chamber of one of the burner tubes showing the manner of mounting the flap valve for closing the lowermost

of the gas inlet passages leading to the 55 burner proper, and

Fig. 6 is a sectional view taken on line 6—6 of Fig. 5.

Similar reference characters throughout the several views indicate the same parts. 60

In the manufacture of gas stoves of the type designed for heating materials adapted to be carried in vessels to be placed upon the stove, it is essential that burners be provided which can be quickly and readily 65 moved to relatively different heights with respect to the top of the stove for the burning of either natural or artificial gas due to the differences in heating qualities and pressure at which these gases are delivered 70 to the consumer. In localities where both gases are obtainable and where purchasers of stoves or burners may desire to burn either natural or artificial gas it is found desirable that the manufacturers be able to 75 furnish the distributor with burners so constructed that the gas discharge ports of the burner may be drilled by him for the use of either artificial or natural gas after the distributor learns the particular kind of gas 80 the customer intends using. With this idea in view I have provided an invertible burner so constructed that the gas discharge ports may be drilled upon one side for the use of artificial gas and upon the opposite side 85

for the use of natural gas, it being understood that the relative positions of the burner with respect to the top of the stove are such as to give the best results in the burning of the two gases. However, the 90 burners may be furnished to the distributor drilled upon opposite sides for the use of both gases and provided with a valve adaptable for closing the gas inlet passageway leading to the lower face of the burner regardless of what position said burner is placed in upon the stove. In a burner of this kind the only movable part is the burner itself, and in the changing of the position thereof it is only necessary to invert the same, which can be quickly done without the use of tools or the disconnecting of any additional parts of the stove.

Referring to the drawings by numerals, 1 represents the top of a stove or range 105 which may be either closed by the use of suitable plates (not shown) or provided with the usual open grids for supporting the

utensils to be placed upon the stove. The top is supported by the side and rear walls 2 and 3 respectively, upon which is also carried the top wall 4 of the oven.

5 The manifold or gas supply pipe 5 is provided with any desired number of stop cocks 6, the nozzles 7 of which project through the hubs 8 of the apertured cap plates 9, each of which is carried upon an enlarged 10 outer end 10 of the burner tubes 11 and 11^a into the mixing chamber 12 of which the nozzles project. Each of the burner tubes is provided with a partition wall 13 dividing the tube into two separate gas delivery 15 passageways 14 and 15 which communicate with the burner chambers 16 and 17 respectively separated by the plate 18. The plate 18 divides the central portion 19 as well as the tips or branches 20 of the burner into 20 entirely separate and distinct chambers.

The opposite and outer faces of the burners are provided with the gas discharging ports or apertures 21 as shown in the several figures of the drawing. The burners are 25 preferably provided with central openings 22 which serve as passageways through which additional air may pass to afford more complete combustion in the burning of the gas beneath the vessels to be placed upon 30 the stove. It will be seen by referring to Figs. 3 and 4 that the burners proper are offset with respect to the outer ends of the gas delivery tubes which are cast integral with said burners. By constructing the burners 35 in this manner they may be moved to relatively different heights with respect to the top of the stove. In Fig. 3 the burner is shown in its lowermost position, in which position it is adapted for burning natural 40 gas, while in Fig. 4 the position of the burner has been elevated to burn artificial gas by merely reversing the same. The rear ends of the front burners are supported on fixed cross bars 23, while the rear ends of 45 the back burners are preferably carried by the projections 24 on the back wall 3 of the stove. The projections 24 are provided with recesses 25 in which the extensions 26 of the rear burners are positioned and held against 50 lateral movement. The supply tubes 11^a leading to the rear burners are adapted to rest upon the cross bar 23 and at the rear edge of the bar the tubes are provided with the projections 27 which prevent accidental 55 displacement of the burners longitudinally of the stove. The cross bar 23 is preferably supported in the recessed projections 28 upon the sides 2 of the stove, and is provided with upstanding portions 29 carrying projections 30. The front burners are provided 60 with extensions 31 which are adapted to rest upon the upstanding portions 29, said extensions having openings 32 through which the projections 30 extend to prevent acci- 65 dental displacement of the burners. The

front ends of the burner tubes 11 and 11^a are each supported by the nozzles 7 of the stop cocks 6. Pivotaly mounted upon the pins 33 at the front ends of the partition walls 13 of the delivery tubes are the flap valves 70 34 for closing the passageways 14 and 15 leading to the burners proper. The front ends of the tubes are provided with shoulders or seats 35 upon which the valves 34 rest as shown in Figs. 3 and 4. The valves 75 34 are acted upon by gravity to close the lowermost passageway whenever the burner is inverted or moved from the position shown in Fig. 3 to that shown in Fig. 4, or vice versa, so that the supply of gas will 80 always be directed to the upper face of the burner in either of the positions shown. The extensions 26 and 31 of the front and back burners are each positioned upon the burners in such a manner as to place the 85 burners in proper relative position with respect to the top of the stove for the burning of either natural or artificial gas. In the center of the stove I have provided a simmering burner 36 carried by the supply tube 90 37 resting upon the cross bar 23. The front end of the tube 37 is enlarged at 38 to provide a mixing chamber for the air and gas entering the tube. The outer end of the tube is supported by the nozzle 7 of the stop 95 cock 6.

I claim as my invention:

1. An invertible gas burner provided with gas discharge ports upon its upper and lower sides, gas supply tubes communicating with 100 said ports and a pivoted valve adapted to close the tube communicating with the ports at the lower side of the burner in either position thereof.

2. A gas burner provided with gas ports 105 on its upper and lower faces, means for supporting said burner in either erect or inverted position, and means for directing a supply of gas to the ports on its upper face when in either position.

3. An invertible gas burner provided with gas discharge ports upon opposite sides thereof, gas supply tubes leading to said ports, and means automatically closing the tube leading to the ports upon the lower 115 side of the burner in either position of the latter.

4. A gas burner provided with gas ports on its upper and lower faces, independent gas supply conduits leading to said ports, 120 means for supporting said burner in either erect or inverted position, and means for automatically closing the conduit leading to the ports on the lower face when the burner is inverted.

5. A gas burner provided with gas ports on its upper and lower sides, independent gas supply conduits leading to said ports, means for supporting the burner in either erect or inverted position, and means for 125 130

closing the conduit leading to the ports on the lower face of the burner in either position thereof.

6. The combination with a gas stove body comprising a top and an invertible burner projecting beneath the top and arranged to extend at relatively different heights with respect thereto when inverted, said burner being adapted to discharge gas from its upper face in either of said positions.

7. The combination with a gas stove body comprising a top and an invertible burner projecting beneath the top provided with gas emission orifices in its opposite faces and arranged to extend at relatively different heights with respect thereto when moved from one position to another and means connected with the burner for automatically preventing the escape of gas from its lower face in either of said positions.

8. The combination with a gas stove body comprising a top and an invertible burner projecting beneath the top provided with gas emission orifices in its opposite faces and arranged to extend at relatively different heights with respect thereto when inverted and means for preventing the escape of gas from the lower face of the burner in either position thereof.

9. The combination with a gas stove body comprising a top and an invertible burner projecting beneath the top and arranged to extend at relatively different heights with respect thereto when inverted, said burner being provided with gas discharge ports upon its opposite faces, delivery tubes leading to each side of the burner in communication with said ports and means for closing the tube leading to the lower side of the burner in either position thereof.

10. The combination with a gas stove

body comprising a top and an invertible burner projecting beneath the top and arranged to extend at relatively different heights with respect thereto when inverted, 45 said burner being provided with separate chambers at opposite sides thereof for burning different kinds of gas, the chamber corresponding to the kind of gas to be used being provided with discharge ports, and a 50 delivery tube provided with passages leading to said chambers.

11. The combination with a gas stove body comprising a top and an invertible burner projecting beneath the top provided with 55 gas emission orifices on its opposite sides and arranged to extend at relatively different heights with respect thereto when inverted, said burner being adapted to discharge gas from its upper face in either of 60 its inverted positions.

12. The combination with a gas stove body comprising a top and an invertible burner projecting beneath the top and arranged to extend at relatively different heights with 65 respect thereto for burning either artificial or natural gas, said burner extending horizontally in either position of adjustment, one side of the burner to be provided with gas discharge ports when it is desired to 70 burn natural gas and the other side with gas discharge ports when it is desired to burn artificial gas.

13. An invertible burner having gas emission orifices in its opposite sides and provided 75 with means for automatically directing a supply of gas through the upper side thereof in either of its positions of adjustment.
